Primary Examiner — Nathan M Johnston

(74) Attorney, Agent, or Firm — Hoffmann & Baron, LLP

(57) **CLAIM**

The ornamental design for a hand operated medical instrument, as shown and described.

DESCRIPTION

FIG. 1 is a top, front and left side perspective view of a hand operated medical instrument showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines show portions of the design that form no part of the claimed design.

1 Claim, 7 Drawing Sheets---
